P. McGINLEY

RAILROAD RAIL JOINT

Filed May 14, 1926

Inventor
Peter McGinley
John Bilton Peter
his Attorney

UNITED STATES PATENT OFFICE.

PETER McGINLEY, OF NEWARK, OHIO.

RAILROAD-RAIL JOINT.

Application filed May 14, 1926. Serial No. 109,052.

This invention relates to structural features involved in the construction or laying of railroad tracks and has for its object the provision of a novel rail joint.

5 An important object of the invention is to provide a rail joint so constructed and arranged as to eliminate shock and jar to the cars or other rolling stock passing thereover.

Another object of the invention is to provide a rail joint embodying an intermediate or connecting element designed to be interposed between the ends of rail sections and having interfitting relation therewith, the contacting portions of the intermediate mem-

15 ber or connector and the rails being arranged at an incline or on an angle with respect to the longitudinal axis of the rail so as to avoid having a joint straight across the rail as is the ordinary construction, it being clear 20 that shock and jar will thus be reduced if not entirely eliminated.

A further object of the invention is to provide a rail joint embodying the combination with the inclined tapered ends of the rail 25 sections, of an interposed block-like member having conforming interfitting engagement therewith, and fish plates of special construction located at opposite sides of the interposed block member and rail sections and 30 secured thereto.

An additional object is the provision of a joint of this character which will be simple and inexpensive to make and install, positive in action, efficient and durable in service, 35 and a general improvement in the art.

With the above and other objects and advantages in view, the invention consists in the details of construction and arrangement of parts to be hereinafter more fully described and claimed, and illustrated in the 40 accompanying drawing, in which:

Figure 1 is a top plan view of the rail joint,

45 Figure 2 is a bottom plan view thereof, Figure 3 is a cross section taken on the line 3—3 of Figure 1, and

Figure 4 is a horizontal section taken on the line 4—4 of Figure 3.

Referring more particularly to the drawings, the numeral 10 designates the adjacent 50 ends of rail sections which in the carrying out of the invention are cut away as indicated at 11, along an incline, the angular inclination of both being preferably, though not necessarily, the same so that the inclined faces will be at least substantially parallel.

At the extremities of the rail sections are formed square shoulders 12. The inclined surfaces 11 are concaved at the ends thereof most remote from the extremities of the rail 60 sections, or in other words these inclined surfaces merge into curved surfaces 13 which extend to the outer sides or edges of the rails. It will be observed that this particular cutting away of the ends of the rails or sections 65 extends entirely through the rails, that is to say the treatment is the same in the ball or tread, the web and the base as will be readily apparent from an inspection of Figures 1 and 2, in particular.

70 For connecting the sections or rails, I provide a block-like member indicated as a whole by the numeral 14, which member is interposed between the adjacent ends of the rails or sections 10, this block-like member 75 including a tread portion 15, a web 16 and a base 17 conforming exactly to the cross sectional configuration of the rails themselves. This interposed member 14 has its opposite 80 sides straight to align or register with the side edges of the rail sections, and the ends of the member are cut away or otherwise formed to define inclined surfaces 18 at the outer ends of which are convex curved walls 19. At the other ends of the inclined surfaces 18 are square shoulders 20. The surfaces 18 of the member 14 lie conformingly against the inclined surfaces 11 at the ends of the rails with the curved surfaces 13 and 19 likewise engaging and the shoulders 12 90 and 20 abutting.

95 In conjunction with the interposed block member 14, use is made of a pair of angular fish plates 21 disposed against opposite sides of the member 14 and the adjacent portions of the rail sections, these fish plates conformingly engaging against the web portions and upon the base portions as clearly illustrated in Figure 3. Securing is effected by means of a suitable number of bolts 22 which pass 100 through the fish plates and also through the adjacent end portions of the rails and the interposed member 14. The outer edges of the fish plates are represented as notched at 23 for the accommodation of spikes by means 105 of which securing to the ties at this point may be effected.

110 In the use of the device, it will be readily apparent that the interposed member 14 constitutes, in conjunction with the fish plates and bolts, a highly efficient connecting means for the rail sections and, in addi-

tion, it serves as a bridge for connecting the ends of the rails in such manner as to avoid the shock and jar which always results from the passage of car wheels over the ordinary joint in which the abutting ends of the rails are straight across. Clearly this will result in a reduction of the wear and tear on rolling stock and also on the rails so that the entire equipment will possess longer life. The provision of the square shoulders takes care of all end thrust so that there will be no shearing strain on the bolts. The bolts of course operate to hold the parts assembled and positively prevent any lateral displacement.

From the foregoing description and a study of the drawings it will be apparent that I have thus provided a simple, inexpensive and easily assembled or installed rail joint structure which will possess all the advantages for which it is designed. It is really believed that the construction, operation and advantages will be readily apparent to one skilled in the art without further explanation.

While I have shown and described a preferred embodiment of the invention, it should be understood that I reserve the right to make such changes in the form, construction and arrangement of parts as will not depart from the spirit of the invention or the scope of the subjoined claims.

Having thus described the invention, I claim:

1. A rail joint comprising in combination with the adjacent ends of two rails substantially correspondingly cut away respectively at opposite sides to define inclined walls and shoulders, a block having its opposite sides straight, the block being interposed between the ends of the rails and having inclined surfaces and shoulders coacting with and conformingly engaging the inclined surfaces and shoulders of the rails, said block having its middle portion formed the full width of the adjacent rails and having a tread, base and web to conform to the rails.

2. A rail joint comprising, in combination with the adjacent ends of rails, said adja-

cent ends being correspondingly cut away at their respective opposite sides to define inclined surfaces merging into concave curved walls extending to the sides of the rails, the extremities of the rails having square shoulders, a block member interposed between the ends of the rails and having its middle portion formed the same width as the rails and including a web, base and tread portion conforming to the rails, the opposite sides of the block member being straight and alining with the sides of the rails, the opposite end of the block member being formed with inclined surfaces merging into convex curved wall portions extending to the sides, the ends of the block member having square shoulders, the inclined surfaces, curved surfaces and shoulders of the block member conformingly engaging against those on the rails.

3. A rail joint comprising, in combination with the adjacent ends of rails, said adjacent ends being cut away at their respective opposite sides to define inclined surfaces merging into concave curved walls extending to the sides of the rails, the extremities of the rails having square shoulders, a block member interposed between the ends of the rails and having its middle portion formed the same width as the rails and including a web, base and tread portion conforming to the rails, the opposite sides of the block member being straight and alining with the sides of the rails, the opposite ends of the block member being formed with inclined surfaces merging into convex curved wall portions extending to the sides, the ends of the block member having square shoulders, the inclined surfaces, curved surfaces and shoulders of the block member conformingly engaging against those on the rails, fish plates engaging against opposite sides of the web portions of the rails and the block member, and securing elements passing transversely through the fish plates and the webs.

In testimony whereof I affix my signature.

PETER McGINLEY.
